UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

STEAM-HEATING APPARATUS.

1,120,319.

Specification of Letters Patent.

Patented Dec. 8, 1914.

Application filed August 9, 1910. Serial No. 576,382.

To all whom it may concern:

Be it known that I, JAMES F. McELROY, a citizen of the United States, residing at Albany, county of Albany, State of New York, have invented certain new and useful Improvements in Steam-Heating Apparatus, the following being a full, clear, and exact disclosure of the one form of my invention which I at present deem preferable.

10 For a detailed description of the present form of my invention, reference may be had to the following specification and accompanying drawings forming a part thereof, in which—

15 Figure 1 shows a vertical section of a structure embodying my invention; Fig. 2 shows the same, applied to the heating system of a railway car; Fig. 3 is a transverse view of Fig. 2.

20 In my present invention I employ a single thermostatic controller subjected to the discharge from the radiator outlet, but I so connect this controller with both valves that it will operate either valve alone, or will op-

25 erate them both together. By this means I am able with the use of only one controller to convert the system to either a high-pressure or a low-pressure system, or to make it an intermediate system.

30 Referring to Fig. 1 which shows a vertical section of my apparatus, the whole is inclosed in a casing in which there are three ports, viz: port 1 for the incoming live steam from the train-pipe, port 2 for the in-
35 coming of the discharge from the radiator, and port 3 (shown in dotted lines) for the outgoing live steam to the radiator.

The live steam from the train-pipe entering port 1 arrives in chamber F and then 40 passes through the hand-operated valve D (which we may assume to be open) into chamber G. Thence it passes through inlet valve A, if that valve is open, into chamber H, from which it passes out through port 3 to the radiator. After going through 45 the radiator and there giving up most of its heat, it returns as water and condensed steam to the port 2 and enters chamber K. Thence it passes outlet valve B, if that valve 50 is open, and falls upon the thermostatic controller C. That controller is of well known construction and need not be described at length. In brief it comprises a sealed expansible vessel C³ containing a substance capable of expanding by heat and so

enlarging or contracting the vertical dimensions of vessel C³ according to the temperature to which it is subjected. As C³ expands, against the force of a spring C², it forces upward a rod C' carrying the outlet 60 valve B and tending to close the same against its seat and, under certain conditions will do so. The rod C' is also connected to the inlet valve so that an auxiliary adjustment of said valve may be obtained 65 as follows: On the upper end of rod C' is a rotatable cap E having a spiral cam on its upper side. Cap E is rotated by means of rotary rod E⁶ which extends upward therefrom and enters a recess in the top of the 70 casing where it is provided with two radial arms E⁷ and E⁸, between which is a pin E⁹ mounted eccentrically on the rotary stem E¹⁰ which has a handle E¹¹. By turning handle E¹¹, the cap E may be rotated any 75 desired degree within limits fixed by stops E¹² between which plays an arm E¹³ on rod E⁶.

On the aforesaid spiral cam on the upper side of cap E bears one leg E' of an angle 80 lever, whose opposite leg E² is connected by link E⁴ to a nut E¹⁴ on the stem E⁵ of the inlet valve A. By means of said nut E¹⁴ any desired initial adjustment of valve A may be obtained. A spring E³ may be applied to the angle lever, if desired, although the steam pressure on valve A will tend to press the leg E' against the cam.

The arrangement just described constitutes what may be called a determining connection of the controller with respect to the inlet valve A, the rotating cap E being the determining agency and the operation being as follows: If the cap E is turned so that the maximum vertical thickness of its spiral cam comes under the extremity of leg E' of the angle lever, then the controller will operate to close inlet valve A, outlet valve B remaining open, since valve A will come against its seat and close while valve B will not, assuming that the rod C' of the controller rises by reason of the expansion of vessel C³ upon a rise of temperature in the discharge water delivered on it from the radiator. The system will then be a low pressure system suitable for milder weather, the admission of steam to the radiator being controlled at the inlet point. On the other hand, when the cap E is turned so that the minimum vertical thickness of its spiral cam 105

comes under the tip of leg E' of the angle-lever, then the controller will operate to close outlet valve B, the inlet valve A remaining open, since the outlet valve B will 5 come against its seat and close, but inlet valve A will not. The system then becomes a high pressure system, suitable for the coldest weather, there being no restriction on the admission of steam to the radiator 10 pipes through the inlet valve, while the controller will only open the outlet valve to allow escape of the water of condensation which has parted with its heat.

By turning the cap E part way the system 15 will be made of an intermediate character, both inlet and outlet valves closing at the same time.

In Figs. 2 and 3 I have shown the above described apparatus applied to a railway 20 car. O is the train pipe from which live steam is conducted through branch pipe P to port 1. S is a pipe conducting steam from port 3 to the radiator pipes T of the car. R is the return pipe from the radiator 25 which communicates with port 2.

What I claim as new and desire to secure by Letters Patent is:

1. In a steam heating apparatus, the combination with a radiator, of an inlet valve, 30 an outlet valve, a thermostatic controller, operating connections between said controller and the said valves, said operating connections including means for initially adjusting one of said valves and also independently adjustable means interposed between said controller and the said initial adjusting means whereby either valve may be closed while the other remains open.

2. In a steam heating apparatus, the combination with a radiator, of an inlet valve, 40 an outlet valve, a thermostatic controller arranged in the path of discharge from the outlet valve, operating connections between said controller and the said valves, said operating connections including means for initially adjusting one of said valves, and also including independently adjustable means interposed between said controller and the said initial adjusting means, whereby either valve may be closed while the other remains open.

3. In a steam heating apparatus, the combination with a radiator, of an inlet valve and an outlet valve therefor, an operating 50 controller for said valves, operating connections between said controller and the said valves, said operating connections including a local adjusting device for one of said valves, and also including an independently adjustable connection between said controller and the said local adjusting device, whereby either valve may be closed while the other remains open.

4. In a steam heating apparatus, the combination with a radiator, of a casing having

an inlet and an outlet for the radiator, valves controlling said inlet and outlet respectively and located within the casing, an operating controller for said valves located exteriorly of said casing, and an operating connection between the controller and valves including means for initially adjusting one of said valves and auxiliary adjusting means whereby either valve may be closed while the other remains open.

5. In a steam heating apparatus, the combination with a radiator, of a casing having an inlet and an outlet for said radiator, an inlet valve within said casing, an outlet valve also within said casing, a thermostatic controller located exteriorly of said casing, and an operating connection between the controller and the valves including means for initially adjusting one of said valves and auxiliary adjusting means whereby either valve may be closed while the other remains open.

6. In a steam heating apparatus, the combination with a radiator, of an inlet valve, an outlet valve, a thermostatic controller, operating connections between said controller and the said valves, said operating connections being provided with means for initially adjusting one of said valves and including an independent cam interposed between said controller and the said initial adjusting means, and means for adjusting said cam, whereby either valve may be closed while the other remains open.

7. The combination with a steam radiator, of a thermostatic controller, an inlet valve mounted independently of said controller, an outlet valve carried by said controller, and an adjustable connection between said inlet valve and said controller including means independent of said adjustable connection for adjusting the said inlet valve.

8. The combination with a steam radiator, of a thermostatic controller, an inlet valve mounted independently of said controller, an outlet valve carried by said controller, an operating arm for said inlet valve, means for initially adjusting said inlet valve relative to its seat, and an adjustable connection between said operating arm and said controller.

9. The combination with a steam radiator, of a thermostatic controller, an inlet valve mounted independently of said controller, an outlet valve carried by said controller, means for initially adjusting said inlet valve relative to its seat, a cam carried by said controller, an operating arm for said inlet valve engaging said cam, and means for moving said cam.

10. The combination with a steam radiator, of a thermostatic controller, an inlet valve mounted independently of said controller, an operating arm for said valve, an adjustable connection between said arm and

said valve, an outlet valve carried by said controller, and an adjustable connection between the operating arm of said inlet valve and said controller.

5 11. In a heating apparatus, the combination with a radiator, of an inlet valve, an outlet valve, a thermostatic controller connected with the outlet valve, a cam carried by the controller, an operating connection 10 between the cam and the inlet valve, and

manually operable means controlling the cam whereby either valve may be closed while the other valve remains open.

In witness whereof I have hereunto set my hand, before two subscribing witnesses, 15 this 14th day of July, 1910.

JAMES F. McELROY.
